UNITED STATES PATENT OFFICE.

ANDRÉ MICHELIN, OF PARIS, FRANCE.

AIR-COMPRESSOR COMBINED WITH AN EXPLOSIVE-MOTOR.

No. 854,371.

Specification of Letters Patent.

Patented May 21, 1907.

Application filed December 14, 1906. Serial No. 347,806.

To all whom it may concern:

Be it known that I, ANDRÉ MICHELIN, a citizen of the Republic of France, and a resident of 105 Boulevard Péreire, Paris, in the 5 said Republic, engineer, have invented a new and useful Air-Compressor Combined with an Explosive-Motor, of which the following is a specification.

The object of this invention is to provide a 10 compressor combined with an explosive motor so that sufficient pressure can be obtained from the motor, for service either in inflating a pneumatic tire or in actuating any apparatus operated by compressed air, such 15 object being accomplished by the employment of air abstracted from the explosive motor during the period of compression and then further compressed by means of the pressure of the same air as the motor is in the 20 act of compressing.

This invention contemplates the use of a piston in a compressor which is reciprocated by air fed from the motor, the said piston being utilized for driving the single-acting pistons of two air compressor cylinders for the 25 purpose of supercompression of the air.

In the accompanying drawings, Figure 1 is a section of a compressor constructed according to the present invention, Fig. 2 is an 30 end view of the same, and Figs. 3 is a diagrammatic view showing the compressor connected to a four cylinder motor.

The compressor comprises a large piston *a* which reciprocates in the main cylinder *b*. 35 This piston *a* drives the two single-acting compressor pistons *d d'* of smaller diameter through the interposition of strong springs *c c'* which serve to absorb the shock at the ends of the strokes of the main piston. 40 These single-acting compressor pistons *d d'* reciprocate in the compressor cylinders *e e'*. The compressor as thus constructed is double-acting and operates effectively on both strokes. The compressor is connected to 45 two of the motor explosion cylinders (or to several pairs of cylinders) by two tubes *f f'* leading to the opposite sides of the main piston *a*. Pipes *i i'* open communication between the compressor cylinders *e e'* and the 50 tubes *f f'* which lead to the opposite sides of the main piston.

Suction valves *g g'* are arranged to open and close communication through the pipes *i i'*. Outlet tubes *j k* lead from the compressor cylinders *e e'* to a single outlet *l*, which outlet may be connected to any suitable

reservoir not shown herein. Exhaust valves *h h'* open and close communication through the outlet tubes *j k*. In the tubes which supply gas to the motor cylinders used for 60 the supercompression, two-way cocks *m m'* are located for closing the supply of gas and opening the supply of air to these cylinders so that these cylinders may either draw in gas when they are desired to work normally 65 or to draw in air where they are to be used in connection with the operation of the compressor. The cylinders of the motor which are not utilized for compressing air may be used for the normal working of the motor. 70

Cocks *n n'* are located in the tubes *f f'* between the cylinders *o o'* of the motor and the compressor so as to be able to assist the operation of the apparatus.

The operation of the apparatus is as follows. The suction cocks *m m'* are turned so as to cut off the supply of gas to the motor cylinders *o o'* and permit the admission of air thereto. The cut-out cocks *n n'* are then opened. When the cylinder *o* arrives at its 80 compression stroke, the main piston *a* is moved from left to right and the compressor piston *d'* will draw in through the suction valve *g'*, the air already compressed in said cylinder. The cylinder *o'* when it arrives at 85 its compression stroke, will in its turn move the main piston *a* from right to left and thus draw into the cylinder *e* the air previously compressed in the cylinder *o'*. The piston *d'* will at the same time expel the air from the 90 cylinder *e'* into the tube *k* through the valve *h'*. The system of pistons will therefore have imparted to them a reciprocating movement synchronous with the travel of the motor and because of the speed of the 95 motor a practically continuous current of air will be ejected through the outlet *l*. When the main piston *a* is returning, the air is reversed into the cylinder of the motor and the said cylinder being open to exhaust, allows 100 the air to escape.

This apparatus is more especially advantageous in connection with automobiles where it may be used for producing the desired pressure for the rapid inflation of pneumatic tires. It may, however, be used for driving by means of compressed air, any form of apparatus as, for example, apparatus mounted on automobiles.

It will be seen that an apparatus constructed hereinabove set forth will be very 112 simple and compact.

What I claim is:

1. The combination with an explosive motor, of a compressor comprising a main cylinder, a piston therein arranged to be reciprocated by air fed from the motor, two compressor cylinders, single-acting pistons therein driven by the first named piston, pipes for opening communication from the opposite sides of the main cylinder to the compressor cylinders, suction valves in said pipes, outlet tubes for the compressor cylinders and exhaust valves for said outlet tubes.
2. The combination with an explosive motor, of a compressor comprising a cylinder, a piston therein, tubes opening communication between the motor and cylinder for the passage of air alternately to the opposite sides of the piston, two compressor cylinders, pistons therein driven by the first named piston, pipes opening communication between the compressor cylinders and the tubes leading from the motor, suction valves for said pipes, outlet tubes for the compressor cylinders and exhaust valves for said outlet tubes.
3. The combination with an explosive motor, of a compressor comprising a cylinder, a piston therein, tubes opening communication between the motor and cylinder for the passage of air alternately to the opposite sides of the piston, cocks in said tubes, two compressor cylinders, pistons therein driven by

the first named piston, pipes opening communication between the compressor cylinders and the tubes leading from the motor, suction valves for said pipes, outlet tubes for the compressor cylinders and exhaust valves for said outlet tubes.

4. The combination with a multi-cylinder explosive motor, tubes for supplying gas to the motor cylinders and cocks for cutting off the gas supply and supplying air to certain of the motor cylinders, of a compressor comprising a cylinder, a piston therein, tubes opening communication between the motor and cylinder for the passage of air alternately to the opposite sides of the piston, two compressor cylinders, pistons therein driven by the first named piston, pipes opening communication between the tubes leading from the motor to the compressor cylinders, suction valves for the said pipes, outlet tubes for the compressor cylinders and exhaust valves for said outlet tubes.

In testimony, that I claim the foregoing as my invention, I have signed my name in presence of two witnesses, this third day of December, 1906.

ANDRÉ MICHELIN.
